UNITED STATES PATENT OFFICE.

FRANCIS K. FASSETT, OF DAYTON, OHIO, ASSIGNOR TO THE NATIONAL CASH REGISTER COMPANY, OF DAYTON, OHIO, A CORPORATION OF OHIO, (INCORPORATED IN 1908.)

REGISTERING MECHANISM.

1,132,711.

Specification of Letters Patent. Patented Mar. 23, 1915.

Application filed September 23, 1907. Serial No. 394,186.

To all whom it may concern:

Be it known that I, FRANCIS K. FASSETT, a citizen of the United States, residing at Dayton, in the county of Montgomery and State of Ohio, have invented certain new and useful Improvements in Registering Mechanism, of which I declare the following to be a full, clear, and exact description.

This invention relates to calculating machines and its prime object is to provide a machine of this class which will permit very fast operation without causing a wrong registration or printing, or impairing the mechanism, and to provide a mechanism which is positive in its action, wherein springs are almost wholly eliminated, and in which all operations are performed during the forward movement of the operating handle.

Another object is to provide a calculating machine wherein each operation is completed by a single movement forward and backward of the operating handle.

Another object is to provide in calculating machines a reversible counter so that amounts may be directly subtracted by the controlling keys simply by changing the position of the counter reversing lever.

Another object is to provide a lever by the manipulation of which the machine adds, subtracts or prints a total, and a second lever which causes the machine to print a grand total and clear itself, but in which neither of these levers effects any irreversible change of the state of the machine. They may be moved at will and if restored to their former positions before the operating handle has been moved, no different function will be performed by the machine than if the levers had not been moved.

Another object is to provide an improved form of key operated controlling device or stop bar wherein said bar is differentially movable by sliding engagements with the keys.

Another object is to provide a differential stop bar and a key detent plate which may be instantly readjusted after being set by one key by the mere depression of another key of the same bank for the purpose of correcting a mistake in depressing the wrong key.

Another object is to provide improved printing mechanism that may be readily adjusted so as to throw the type bars against the platen with different degrees of force

and to provide means for preventing the printing members from rebounding or vibrating against the type bars.

With these and incidental objects in view the invention consists in certain novel features of construction and combinations of parts the essential elements of which are set forth in appended claims and a preferred form of embodiment of which is hereinafter disclosed with reference to the drawings which accompany and form part of this specification.

Of said drawings: Figure 1 is a central longitudinal section of a calculating machine constructed according to this invention. Fig. 2 is an enlarged detail of the counter actuating mechanism. Fig. 3 is a section on the line 3-3 of Fig. 2. Fig. 4 is a front elevation of the mechanism shown in Fig. 2. Fig. 5 is a top plan partly in section and partly broken away of the counter actuating mechanism. Fig. 6 is an enlarged view and more in detail of some of the operating mechanism shown in Fig. 1. Fig. 6^a is a view similar to Fig. 6, with a number of the parts left out for the sake of clearness. Fig. 6^b is a view of the remaining parts shown in Fig. 6, but left out of Fig. 6^a. Fig. 7 is a detail of the key releasing device. Fig. 8 is an enlarged front elevation of the counter. Fig. 9 is a longitudinal section of the same. Fig. 10 is a side elevation of one of the counter wheels. Fig. 11 is a section on the line 11-11 of Fig. 8. Fig. 12 is a detail of the transfer device and is a section on the line 12-12 of Fig. 9. Figs. 13 and 14 are details of cams shown in Fig. 12. Fig. 15 is a detail of the operating mechanism of the counter transfer device. Fig. 16 is a detail of the resetting mechanism. Fig. 17 is a rear elevation of the same. Fig. 18 is a detail view of a portion of the printing mechanism with the parts shown in partially operated positions. Fig. 19 is a view similar to Fig. 18 with the parts shown farther advanced in their operation.

The machine of the present invention is intended to provide a positively operating adding and subtracting mechanism, thereby securing an accurate and at the same time very rapid machine. The keys when depressed are arranged to differentially adjust stop mechanism which is in the path of two sets of complementarily stepped

slides. When the machine is operated the slides are moved until the complementary steps thereof abut the differential stops to cause a differential operation of the adding mechanism through racks carried on one set of the stepped slides. Also connected to one of the sets of slides are type bars which have series of type from zero to nine thereon and which are differentially adjusted to bring 10 any desired type opposite the printing point by the differential movement of the stepped slides. A printing hammer is provided for each of the type bars with means for throwing all of the hammers with varying degrees of force against said bars so as to cause an impression therefrom to be taken on the record material. The type bars are normally out of zero printing position and are arranged to be elevated one step so as to 20 bring the zero type to printing position if any type bar of higher denomination has been adjusted. In case a type bar is not raised at all, the printing hammer for that denomination is locked in retracted position 25 by the type bar so that no operation of the printing hammer is given.

Means for printing totals at any time without resetting the counter wheels are provided, the said means comprising stepped 30 cams movable with the counter wheels, and with which stepped cams levers controlling the differential stops previously referred to are associated, so that the differential stops may be adjusted into the path of the stepped 35 slides in accordance with the amounts previously added on the counter. When an operation of the machine is then given the total will be printed on the record material. By changing the position of a resetting lever 40 it is also possible when printing a total to reset the counter to zero and restore the machine to a condition ready to receive a new registration by the same movement of the operating handle which causes the ordinary 45 printing of totals.

The mechanism is designed to subtract as well as to add by merely shifting laterally the racks which cause the operation of the counter. When they are so shifted laterally the racks are adapted to engage intermediate gears which reversely move the counter.

With this general description it will be seen that the mechanism to be described 55 includes the key board mechanism, the mechanism having the differential motion, the counter mechanism including transfer devices therefor, the printing mechanism, means for printing totals, and means for resetting the counter to zero together with some details such as a full stroke device and a releasing mechanism for the keys.

Key board and differentially operated mechanism.—The machine is provided with 60 a plurality of banks of keys numbered from

one to nine inclusive, only one of which banks is shown in the drawings. The keys when depressed are adapted to engage the cam edges 19 of a stop bar 18 and move the latter rearwardly differentially. As best 70 shown in Fig. 1 it will be seen that the cam edges 19 increase in length from front to rear so that the keys when depressed will impart a variable movement to the bar 18. The usual detent 21 is provided to retain 75 any key in depressed position. It will be seen from the shape of this detent plate 21 that the depression of any key will release a previously depressed key. Means hereafter described are provided for moving the key 80 detent 21 at the end of each operation of the machine so as to release the depressed key. If a key has been depressed by mistake, say for instance the "nine" key which is the 85 rearward one and it is desired to depress a key of lower value, all that is necessary is to depress the proper key, which will release the "nine" key and readjust the stop bar 18 by contacting with one of the cam edges 20 formed on said bar. Between each cam edge 19 and its corresponding edge 20 a straight portion of the stop bar is provided against which the lower camming edge of the keys will abut so as to lock the bar in its adjusted position.

Near the end of the operation of the machine the stop bars 18 are returned to normal or zero position which is the position shown in Fig. 1, by springs 22, the ends of which are fastened to downward extensions 95 of the stop bars 18 and a cross rod 23. This rod 23 is supported in the upper ends of levers 24, the lower ends of the latter being pivoted to the side frames of the machine as at 25. A shaft 29 to which an operating 100 handle 28 is secured to one end, is provided with a cam 60 near each end. These cams 60 contact with pins 24^a projecting from the levers 24 at the beginning of the movement of the rock shaft 29 by the operating handle 28 and thereby put the springs 22 under tension. These springs 22 remain under tension until after the keys are released and the hereinafter described slides 32 and 33 returned to normal position. The stop bars 115 18 are guided and limited in their rearward and forward movements by pins 30^a projecting from cross braces 30^c of the machine frame. Normally the springs 22 are not under tension so that the differential 120 stop bars 18 may be moved rearwardly with very slight effort.

The differential stops 18 are carried by rollers 30 projecting from the cross brace 30^c and guided by the pins 30^a passing 125 through slots as shown in Fig. 1 and are provided at their rear ends (see Fig. 2) with flanges 31 in the paths of stepped slides 32 and 33. The stepped slides 32 and 33 are provided at their lower ends with racks 34 130

and 35 respectively, which latter are in constant mesh with pinions 58 loosely mounted on shaft 27. At one end of shaft 29 the main operating lever 28 is rigidly secured, 5 Levers 36 pivoted at 37 and carrying pins 38 which enter the slots 39 in cams 60 carry at their free ends the shaft 27. Only one of each of these parts is shown in the drawings. It is clear that at each forward movement of 10 the handle 28 the shaft 27 will be lifted an invariable distance. This lifting will begin almost immediately after the handle 28 begins to move and will reach its highest point when the handle has moved about one 15 half of its distance forward. The shaft will remain in its elevated position until the handle 28 has completed its forward movement and about half of its return movement. During the remainder of the return movement 20 of the handle the shaft 27 will return to its lowest position.

The serrations on slides 32 and 33 are stepped so that the slides may engage the differential stop bars 18 at different positions along their length and stop the slides 25 at different positions along the path of their movement. The differential stop bars are for this purpose movable transversely to the movement of the slides into alignment 30 with any of the serrations on the slides.

It will be seen from this description that the operation comprises a depression of the proper keys and a movement forward and return of the operating handle. When the 35 keys are depressed, the differential stop bars 18 are moved forwardly, and the flange 31 of each stop bar is thereby brought to the proper obstructing position. As the handle is drawn forward, the shaft 27 is elevated 40 a constant distance, or, in other words, is given invariable excursions at all operations, the elevation of the shaft occurring during the first half of the forward movement of the handle. The counter racks 41 45 and operating slides 33 thereof are retarded at the beginning of their upward movement, by spring pressed pawls 47, loose on the rod 48. The result of this pawl construction is that the slide 33 is retained in its normal 50 position when shaft 27 is elevated, so that the pinions 58 rotate around this shaft as the shaft moves upwardly, thereby elevating the slide 32 twice as fast as the shaft moves. At some point in the elevation one of the 55 serrations of slide 32 will engage the positioned flange 31, thereby obstructing and stopping the slide 32, whereupon the said slide becomes the fulcrum for pinion 58, and this pinion throughout the remainder of the 60 upward movement of the shaft 27 rotates in the opposite direction, thereby elevating the slide 33 and counter rack 41. As the shaft 27 reaches its highest position, the slide 33 will engage one of its serrations 65 with the said flange 31 so that the whole

mechanism is then locked, and the operation of the counter has taken place. During the second half of the forward movement of the handle, the counter operating mechanism remains in elevated position, and this 70 is also true during the first half of the rearward movement of the handle. During the latter half of the rearward movement the shaft 27 is moved downward to its normal position carrying both slides and the counter 75 rack 41 with it to their respective normal positions.

It will be seen that the movement of the stepped slides 32 and 33, when the shaft 27 is raised, is complementary, the sum of the 80 motions in all cases being ten spaces, and it will be further seen that in all cases the slides 32 and 33 finally abut flanges 31 of the differential stops 18 so as to positively lock the slides and entirely prevent the possibility of overthrow of the counter wheels. 85

Thus far in the description, it may have been assumed that counter racks 41 are rigidly connected to the slides 33, and this might be the case if no printing mechanism 90 was employed. The construction disclosed, however, provides a lost motion connection between the slides 33 and the corresponding counter racks 41 permitting the slides 33 to be elevated one step before the counter racks 95 41 start to move, this being for the purpose of printing zeros. This construction will be described in detail in connection with the printing mechanism.

The object of retarding the movement of 100 the slides 33 by the pawls 47 is to enable the racks 41 connected to said slides 33 to engage their counter wheels and to withdraw certain locking devices for the said counter before the slides 33 and the racks 41 move 105 upwardly as hereinafter fully described.

Counter and transfer mechanism.—Coming now to the counter itself and the transfer mechanism the detailed description may be premised by saying that the counter comprises a series of wheels bearing numbers on their peripheries which successively pass in the rear of an opening in the casing through which the numbers may be observed. The counter wheels each carry an actuating gear 110 which is adapted to be meshed with the operating racks 41. It will be evident that if the motion of the counter wheels is derived from the racks through intermediate gears the direction of such motion will be 115 opposite to that given when the motion is derived directly from the racks. Such a construction is disclosed herein and clearly provides a simple subtracting mechanism inasmuch as in order to subtract, all that is 120 necessary is to change the connection so that the racks 41 will be meshed with the intermediate gears and not with the counter gears themselves. 125

The counters (Figs. 8, 9 and 10) are 130

turned during the upward movement of the racks 41 which directly mesh with the counter pinions 50 on shaft 51^a during addition and with the intermediate gears 51 while subtracting. In order to subtract the racks 41 are shifted laterally from mesh with the pinions 50 into mesh with the gears 51 so as to reversely turn the counters during the same upward movement. It will be seen from Fig. 8 that gears 50 and 51 are staggered to allow them to be separately meshed with racks 41. The shifting of the racks is accomplished by means of the lever 52 which controls a cam 53 (see Fig. 6) connected to said lever. The cam 53 engages a pin 54 projecting from a shaft 55, and effects a longitudinal shifting of the shaft. Pinned to the shaft 55, as shown in Fig. 5, are guides 56 for the racks 41. The longitudinal movement of the shaft 55 will of course cause said guides 56 to shift the racks 41.

Before proceeding with a detailed description of the counter, some of the operating connections will be described as these parts and the timing of their movement are important to the counter and transfer mechanism.

The counter wheels are normally locked against rotation by the drums 57 on the shaft 49 engaging star wheels 59 which are secured to and revoluble with the counter pinions. The following described mechanism is used for imparting a slight vertical movement to the shaft 49, enough so that the drums 57 will be lifted free from the star wheels to permit actuation of the counter wheels. This mechanism also simultaneously moves the counter racks 41 into and out of mesh at the proper time. Loosely mounted upon the shaft 29 adjacent to one of the cams (see Fig. 1) are a disk 61 and a ratchet 62, the two being united. The ratchet 62 has five notches cut in its periphery with which the pawl 65 (Fig. 6) driven by the operating handle engages. The ratchet 62 and disk 61 will move one fifth of a revolution forward each time the handle 28 which actuates the pawl 65 is moved forward and backward. Backward motion of the ratchet 62 is prevented by the retaining pawl 66. A lever 67 mounted on a shaft 68 has projecting arms 69 and 70 which embrace and co-act with cam surfaces formed on the periphery of the disk 61. It is evident that the lever 67 will oscillate as the disk 61 revolves. The relation of these parts is such that the lever 67 will be rocked forwardly immediately after the operating lever 28 starts to move forward and before the shaft 27 has begun to lift. The lever 67 will remain in the forward position until after the shaft 27 has reached its highest point, when said lever will be immediately rocked to its backward position where it will remain until the next operation of the ma-

chine as the disk 62 remains idle during return of the handle. One end of a rod 71 is carried by the upper extremity of the lever 67, the other end of rod 71 being carried by an arm which is also mounted on the shaft 68, but is not shown in the drawings. The rod 71 passes through elongated openings in the upper ends of the racks 41 and it is clear that the latter will be thrown into mesh with the counter operating gears 50 or 51 as soon as the handle 28 starts and before the shaft 27 begins to lift. The lever 67 also serves to lift the counter transfer and locking devices out of engagement with the counters and hold them in such position while the racks 41 are in engagement with the counter pinions. For this purpose a link 72 is pivoted to the lever 67 and to an arm 73, the latter being a slot and pin connection. The arm 73 carries one end of the transfer shaft 49 and is itself mounted on shaft 74. The other end of the shaft 49 is carried by an arm similar to 73 and is also mounted on the shaft 74.

Transfer mechanism.—The transfer mechanism is adapted to operate in either direction of rotation of the counter wheels, the direction of operation depending on the same means which causes a shifting of the connection between the racks 41 and the counter wheels. The shaft 49 carries beside the locking disks or drums 57 a series of transfer operating devices and this shaft is adapted to be rotated in one direction or the other at each operation of the machine, the direction of rotation depending on whether the machine is to add or subtract. As usual, devices under the control of wheels of lower order are provided adapted to engage the transfer devices with the wheels of higher order. Transfers from wheels of lower order to wheels of higher order are effected by the wheels of lower order camming transfer device 90 into position to engage the counter pinions at the time a transfer is to be turned in, and rotating said transfer devices. The transfer devices 90 are each provided (see Fig. 11) with a pair of teeth 115 and 116 which are adapted to be meshed with the counter pinions. The means for rotating the shaft 49, upon which are mounted the transfer devices, in either direction according to whether amounts are being added or subtracted, comprises a pair of racks 82 and 83 (Fig. 15) which are each adapted to be separately geared to the shaft 49 so as to positively rotate said shaft. By means of the lever 52 the racks 82 and 83 may be oppositely moved so that either one or the other of said racks will mesh with their respective gears. The longitudinal movement of the racks 82 and 83 is effected by means of the following described mechanism: A star shaped disk 75 with ratchet 76 attached is loosely mounted upon the shaft 130

29 and is actuated by the lever 28 through the pawl 77 which is mounted on stud 63 on said lever which also carries pawl 65. The points of the disk 75 co-acting with 5 pins 78 and 79 cause an oscillating motion of the lever 80 which swings on the center 81. This lever will be in its elevated position when the lever 28 is in its rearward position and will descend as the lever 28 moves forward, and having reached its lowest 10 position will ascend during the latter half of the forward movement of the operating handle, at which time the lever 67 is in its rear position and the racks 41 are disengaged from the counter when the lever 67 is rocked into its rear position. The lever 28 returns to its rear position leaving the lever 80 elevated. It will be seen that the transfer shaft is rotated first in one direction 15 and then in the other direction at each operation of the machine, the first rotation being idle inasmuch as the transfer shaft 49 is at this time elevated. The direction of rotation depends on the position of the 20 function lever 52, so that if the lever is in adding position, the first movement of the transfer shaft will be in one direction, while if the function lever is in the subtracted position, the first movement of the transfer 25 shaft will be in the opposite direction. The racks 82 and 83 are guided at their lower ends on studs 84, and a recess formed in their sides embraces a pin 85 extending from the side of the lever 80, so that said racks 30 82 and 83 will move up and down with the lever 80. Pins carried by a pair of levers 86 and 87 guide the upper ends of the racks. The position of the levers 86 and 87 is determined by the pin 92 on lever 93 pivoted 35 at 94, pin 95, and the cam slot on the lever 52. The lever 52 is loosely carried by the shaft 29 and has three positions. When in its central position, which is the position shown in the drawings, if the register is 40 operated addition will take place. If it is in the position farthest from the operator subtraction will take place and when it is toward the operator a total will be printed. When the lever 52 is in its central position 45 the rack 82 will mesh with the gear 96 which is loosely mounted on the shaft 97. The gear 98 secured to the gear 96 meshes with a gear 99 which is mounted on transfer shaft 49. The gear 100 which is engaged by the 50 rack 83 meshes with the gear 96 but with only a portion of the tooth faces, the gear 100 being longitudinally displaced. The teeth on gears 98 and 99 are made rather long to prevent them from becoming disengaged when the shaft 49 is lifted.

The construction of the transfer operating mechanism whereby the shaft 49 is given a movement in one sense or the other, will now be clear, and a specific description of the 55 transfer may now be given.

The counter transfer mechanism is illustrated in Figs. 8, 9, 10, 11, 12, 13 and 14. Loosely mounted upon the counter wheel shaft 101 and within each counter wheel is an arm 102 carrying a conical trip cam 103 which protrudes through an opening 105 in the flange 104 of the counter wheel. This arm is capable of movement independently of the counter wheel to the extent permitted by said opening 105. The transfer shaft 49 70 is in its upper position at the time when the counter wheels are being moved by the racks 41, which permits the extremity of scalloped wheels 59 to pass the drum 57. A lug 108 forming part of a plate 107 normally projects into the hollow of and back of the flange 104 of each of the counter wheels. 75

As a counter wheel passes from nine to zero in addition or from zero to nine in subtraction, its cam 103 having first receded to 80 the limit of the opening 105, moves the lug 108 from the interior of the counter wheel to the exterior of the counter wheel and in doing so moves the member 90 into the same vertical plane as the counter pinion 50. The 85 plate 107 is loosely mounted upon the drum 57 between the cams 110 and 111 which are rigidly secured to the drum 57. Lugs 113 and 114 co-act with the cams 110 and 111 respectively to raise or lower the plate 107 90 with respect to the shaft 49. The transfer plate 95 90 is rigidly secured to the drum 57, the latter being splined to the shaft 49 and free to slide longitudinally on said shaft 49. In Fig. 11 the member 90 is shown in position ready to effect the transfer. The two teeth 115 and 116 formed on its periphery will transfer the former in addition and the latter in subtraction depending upon the direction of rotation of the shaft 49. 100

Assuming that an addition is being made upon the units wheel of the counter which will carry an amount to the tens wheel, the units wheel driven by its rack 41 revolves the number of spaces determined by the 110 amount key pressed. As the numbers seen in the sight opening pass from nine to zero the transfer device is shifted, the lug 108 passing from the interior to the exterior of the counter wheel. All this time the shaft 115 49 with the transfer devices carried thereon is in an elevated position and is revolving in the same direction as that in which the counter wheel is revolving. When the registration begins the plate 107 is in its lowest 120 position with reference to the shaft 49, but during the time the shaft 49 is revolving in its elevated position, the plate 107 actuated by the cams 110 and 111 will be lifted. Simultaneously with the withdrawal of the 125 rack 41 the shaft 49 descends bringing the drum 57 into the sphere of movement of the points on the disk 59 thereby locking the counter wheel against displacement. When the shaft 49 has reached its lowest position, 130

the racks 82 and 83 begin to ascend the former being engaged with the gear 96. The shaft 49 will now be revolving in a direction contrary to that in which the counter wheel has just been revolving and the tooth 115 will engage a tooth of the counter gear 50 and move the counter wheel one unit. In order to permit the counter wheel to rotate on a transfer the drum 57 has in it two cuts 215 and 216 (Figs. 8 and 11) into which the points of the scalloped disk 59 enter as the wheel revolves. The cut 215 is the one used on an adding operation, while the cut 216 is used on subtracting operations. Normally these cuts are not in alignment with the disk 59, but are brought into the same plane when the transfer device is shifted into position to make the transfer. Unless the shift occurs the drum simply turns idly in the scallops of its disk 59 and the counter wheel cannot be rotated. All this time the plate 107 being in its upper position, the lug 108 will be too high to clear the flange 104 of the counter wheel. As soon as the tooth 115 has effected the transfer the cams 110 and 111 co-acting with the lugs 113 and 114 will move the plate 107 to its lowest position in which position the lug 108 can pass under the flange 104. One of the wings 117 now coming in contact with the edge of the gear 50 cams the transfer device toward the counter wheel bringing the lug 108 within the wheel, thereby resetting the transfer devices. Since the teeth 115 and 116 are in the same plane with the plates 90, a swell 109 is formed opposite the teeth which moves the transfer device still farther toward the counter wheel and causes a clearance between the teeth of the counter gears and the plates 90. The shaft 49 continues to revolve until a point midway between the teeth 115 and 116 is uppermost. The distance between the teeth 115 and 116 is least in the plate 107 belonging to the units wheel which is the one shown in the drawings and this distance is greater as the denomination of the counter wheels to which the plates belong increases. This arrangement secures successive action of the transfer devices from lower to higher denominations. For the same reason it is evident that the position of the wings 117 and the positions of the active points of the cams 110 and 111 will be correspondingly different for each denomination.

Printing mechanism.—The printing mechanism in the present case comprises a series of type bars, with means connecting them to the slides 33 so that they are elevated to an amount proportional to that to be added on the counter. It was previously stated, that the connection from slides 33 to the counter racks 41 was not a rigid immovable connection, and that this construction was requisite only when

printing was to be done. For this reason the previous description ignores the type of connection between slides 33 and rack 41, but it will be seen from the drawings that the type carrying bars are rigidly connected to the slides 33 and move with them at all times. When any of the bars are elevated their upper cam edges 120 engage the cut away part of the casing so as to force the type bars slightly rearward enough to release them from the printing hammers which are normally locked by said type bars. One hammer for each type bar is provided and is arranged to rotate around a rod running transversely of the machine and to be operated by springs connecting the hammer device to the operating mechanism. It is sometimes desired to make carbon copies of the list of numbers and in such cases the hammers should strike with more force than if only a single copy is to be made. To accomplish this function there is provided a variable connection of the operating devices for the hammer so that the operating springs may be given more or less tension as desired whereby when the hammer stroke is made, more or less force will be given thereto. This adjustment permits of a greater force being used when the ribbon becomes old, thereby increasing the effective life of the ribbon.

It has been stated that the type bars are normally in such position that the zero thereon is not opposite the printing line. It is desired when any number is printed including one or more zeros that they should be printed although ordinarily zeros are not printed. This function is well known in adding machines for causing the printing of zeros to the right of any operated bank. In this mechanism the function referred to is performed by stopping one of the stepped slides one unit sooner than it would ordinarily be stopped, thereby allowing the other pair of stepped slides to have one unit of movement which serves to thereby bring the zero to the printing point. The construction is such, as has been previously described, that this one unit of movement does not move the rack 41, which movement would cause a false addition on the counter.

The specific construction for producing one step of lost motion between the driving slide 33 and the counter rack 41, may now be given.

The stepped slide 33, is provided, as shown on Fig. 2, with a central projection 42, to which is pivoted a bell crank lever 43, one arm of the bell crank having a cam and a straight edge and the camming portion of which normally surrounds a stationary rod 45. The other arm of the bell crank 43 is pivoted to the counter rack 41. From this construction it will be seen that when the slide 33 is elevated one step, the exten-

sion 42 will also move up, thereby carrying up the pivot of the bell crank 43. The shape of the camming portion of the depending arm of the bell crank is such that the bell crank will be rocked in a counter clock-wise direction around a central pivot during this first step of upward movement, as is clearly evident from the shape of the slot in the bell crank in this figure. The 10 rocking of the bell crank around its pivot, will, as far as the pin and slot connection at the end of the horizontal arm thereof is concerned, entirely negative the upward one step movement of the pivot of the bell 15 crank, so that during the first step of upward movement of the slide 33, the counter rack 41 does not move. This one step of movement, however, is enough to carry the camming part of the slot 44 in bell crank 43, past rod 45, so that during the remaining portion of the upward movement of slide 33, this straight edge moves past the rod 45 and the consequence is that the counter rack 41 moves upwardly with the slide 33 during 20 the remainder of its movement.

The printing hammers 121 (Fig. 1) are pivotally mounted on levers 122 and are swung around a fixed fulcrum 123 upon rocking the levers 122. The roller 124 is 25 carried by two links 125. One of these links is pivoted to the lever 126 and at its lower end to a short arm 127 which is pivoted to the frame of the machine. The other link is carried by a similar arm and at its upper end by a plain lever not shown similar to 126 except that it has no notches 128. The lever 126 is secured to a rock shaft 129 and secured to the same shaft is a lever 130 which is connected by a link 131 to the lever 40 80. (see Figs. 1 and 15). It will be remembered that the lever 80 moves down and up at each operation of the machine. It is therefore clear that the links 125 are drawn down and up positively at each operation of 45 the machine. As the roller 124 rises it positively lifts the levers 122 which bring the small projections 132 forming part of the hammers 121 in contact with the rod 123 and restores the hammers to the position shown 50 in Fig. 1. The rocking of the levers 122 upon their pivot 133 is accomplished by means of springs 134, one end of each of said springs being fastened to one of the levers 122 while the other ends of said 55 springs are fastened to a rod carried at the outer ends of two levers 135 only one of which is shown in the drawings. Normally these springs 134 are not under tension but are tensioned at each operation of 60 the machine when a printing impression is desired. The hammers operate under the action of the springs 134 just as the lever 80 reaches its lowest position when the lug 209 of the lever 126 pushes the catch 210 65 away from the hammers. The levers 135

are secured to a rock shaft 136. The lower end of a throw lever 137 for regulating the amount of oscillation of the shaft 136 is pivoted to one of the levers 135 and the position, in the notches 128, of the roller 70 75 138 carried by the lever 137 determines the amount of expansion to be imparted to the springs 134.

The adjustment of the roller 138 by its operating lever 137 serves to determine the extent of movement of the arms 135 and the consequent amount of tension of the springs 134 before the printing hammers are released. When the hammers are finally released, the springs rapidly contract, thereby rocking the 80 arms 122 around their pivot and rapidly rotating the printing hammers 121 around the rod 123. When the hammers 121 reach a vertical position the springs tend to move them downwardly but their rotative motion 85 is so rapid that the hammer will strike the type carrier and throw the carrier against the platen before the hammer is more than slightly depressed. The further movement of the springs 134 and the further downward movement of the printing hammers will cause the cam notches 157 of said hammers to engage the rod 123 thereby slightly withdrawing the hammers from the type carriers so as to prevent a second blow on 90 the carrier.

The type bars are notched at 139 for the purpose of engaging a co-acting projection on the levers 122 so that the printing hammers will not operate when the type bars 100 are in the position shown in Fig. 1. This is the position of the bars at the beginning of each operation of the machine and during the operation of the machine in case no key of the particular bank which controls the type bar and no keys of a bank of higher denomination have been depressed. When any of the keys of higher denominations are depressed the type bars controlled by keys of lower denominations 105 will, if not otherwise set move up one space so as to bring the zero type opposite the platen. This is accomplished by a series of co-acting pawls 140 (Figs. 2 and 3). One pawl 140 is provided for each of the slides 110 33 and is cammed to one side by the shoulder 141 on the slide so as to throw the extension 142 of all pawls 140 of lower denominations into the path of their respective slides or more properly the shoulders 143 on parts 115 rigid with the slides 32. The slides 32 will then be stopped one gradation less than a full stroke so that the slide 33 will move up the complement gradation and will bring the zero type opposite the platen. Another 120 function of the pawls 140 will now be described. It has been stated that the slides 32 and 33 abut the flange 31 when the shaft 27 reaches its highest point. This is true 125 in all cases where the slide 33 moves at all 130

but (referring to Figs. 1 and 2) the slide 33 will be seen to lack one space of reaching the flange 31 of the stop bar 18. To guard against the possibility of the slide 33 lifting up if its companion slide 32 should tend to rebound after striking the flange 31 in cases where no zero or other figure is to be printed, the upper end of the slide 32 passing behind the projection 142 prevents the pawl 140 from rocking and any tendency on the part of the slide 33 to lift up will be prevented by the projection 141 striking the lug 144 of the pawl.

Printing sub-totals is accomplished by moving the lever 52 to the position shown by dotted lines at the right of Fig. 6 and then swinging the lever 28 a full stroke to the right and return. When the lever 52 is moved to the position mentioned it will by means of the cam slot 145 and pin 146 swing an arm 147 a certain distance to the right. (Cam slot 145 is shown best in Fig. 7.) The arm 147 is rigidly secured to a shaft 148 and arms 149 are also secured to the shaft 148, only one being shown, which carry at their upper ends a rod 150 (Fig. 2) upon which rod are pivotally mounted levers 151 the upper arms of which will before the arm 149 reaches the limit of its stroke, come into contact with serrated disks 152 on the counter actuating gears. The levers 151 will be carried on with the arm 149 but will also swing independently on their pivots with the disks 152 as fulcrums. The lower arms of the levers 151 are provided with extensions 153 which engage depending projections 154 on the differential stop bars 18 and move said stop bars to the left (Figs. 1 and 2) during the remaining movement of the arm 149. The serrations on the disks 90 correspond in distance from the center of the disk to the amounts of the different numbers on the counter wheels and the amount of movement imparted to the differential stop bars will depend on which serrations are opposite the ends of the levers 151. The disks revolve with the gears 51 and one is provided for each counter wheel. Each disk is divided into halves provided with ten steps because the gears 52 only make one revolution to two of the counter pinions. Now upon drawing the lever 28 downwardly a full stroke, the slides 33 and their corresponding type bars will move upwardly until they contact with the differential stop bars. The printing hammers are released and print the total amount which the counters indicate. Thus total printing may be done without resetting the totalizer wheels by moving the function lever 52 to a third position, and thereby setting up the differential stops.

It is necessary while the sub-total is being printed to maintain the racks 41 out of mesh with the counter pinions to prevent turning of the counters. For this reason a pin

155 (Fig. 6) carried by the lever 52 lifts the pawl 65 out of engagement with the ratchet 62 when the lever 52 is moved into position for printing a total. The shaft 29 then rocks without revolving the ratchet 62, the racks 41 remaining out of engagement with the counter pinions and the counter wheels remaining locked. A suitable stop in the form of a stationary rod is provided against which the lower ends of the levers 151 will abut when the lever 52 is in its central or its rear position, to prevent the upper ends of the levers accidentally swinging into the path of movement of the disks 152 during ordinary operations of the machine. 80

It will be seen that when sub-totals are to be printed the only difference in the operation is that the lever 52 is adjusted to its forward position to prevent the racks 41 from engaging the counter wheels and the movement of the differential stops 18 is controlled from the levers 151 and not the keys. 85

The previous description contemplates only the printing of subtotals but it may some times be desired to print the total and 90 at the same time reset the counter to zero or normal position at the same operation. When a grand-total is to be printed and the register reset to zero a lever 158 (Fig. 6) is drawn toward the operator, this action also 95 moving the lever 52 toward the operator by means of a pin 159 on lever 158 abutting a projection forming part of a camming arm 160, which swings on the same center as the lever 158 and at its free end is forked the 10 inner edges of the two links forming cams 161 and 162 the former of which engages the stud 163 carried by the lever 52 and as the lever 158 is moved forward the lever 52 moves into the position required when a 10 sub-total is to be printed.

Resetting mechanism.—To reset the counter when a grand total is printed the following mechanism is provided: Pivoted to the lever 158 (see Figs. 16 and 17) are 110 three links 164, 165, 166. The link 164 is connected to the link 72 (Fig. 6). The link 166 is connected to a rack 167 and by means of this rack the counter is reset to zero. The rack 167 is guided at its upper end by 115 a pin 168 and meshes with a gear 169 which is rigidly secured to the shaft 170. The lower end of the rack 167 has slots cut on opposite sides, the lower one of which embraces a pin 171 which is carried by the 120 frame of the machine. The link 165 is connected to another link 172 whose upper end is connected by a slot and pin connection to a lever 173 which is a companion to the lever 73 except that the slot differs in shape, the 125 slot in lever 173 being so formed as to permit the link 172 to lift a limited distance without lifting the lever or permit the lever to lift when the link remains stationary, that is when the lever 158 is in its normal 130

or rear position. The slot in lever 73 is formed so as to permit the lever to lift when the lever 158 has moved forward the link 72 remaining at rest. The lower end of the 5 link 172 is connected to a forked lever 174 which is mounted upon the shaft 68 and whose extremities 175 and 176 co-act with the toothed periphery of a cam disk 177 secured to and revolving with the star shaped 10 disk 75. Each time the lever 28 is drawn forward and backward the lever 174 will rock downward and then upward the first movement taking place just after the lever 80 reaches its lowest point and before it 15 starts up. The first half of the oscillation of the lever 174 will occur just after the lever 80 has reached its highest point. The second half of the oscillation of the lever 174 raises the link 172, the second half 20 lowers the link.

A bell crank lever 178 pivoted to the frame of the machine at 179 has its vertical member forked and provided with studs which enter a groove cut in the hub of a 25 gear 169. The horizontal member of the lever 178 terminates in a stud 181 which enters an L-shaped slot in the link 172. When the lever 158 is in its rear position the stud 181 will be in the vertical part of the 30 slot of the link 172 which permits the link to lift without rocking the lever 178, but when the lever 158 is forward and the link 172 then lifted the lever 178 will be rocked and the shaft 170 shifted longitudinally. 35 A pendent link 182 connected to the link 172 by a slot and pin swings over the stud 181 when the link is in its rearward position and prevents the shaft 170 from shifting accidentally. The pendent link 182 is supported upon the frame of the machine at 183.

The gears 51 and disks 152 are secured to hubs which are loosely mounted upon the shaft 170. At the outer end of each hub is secured another disk 184 (see Fig. 8) carrying two pins 185 diametrically opposite on the disk. A sleeve 186 with a slot cut in one side is spaced on the shaft between each of the hubs referred to and the space remaining between the last hub on each end of the 45 shaft and the frame of the machine is also filled by a suitable sleeve. This permits the shaft 170 to move longitudinally without displacing any of the hubs, etc. When the lever 158 has been thrown forward to print 50 a grand total and the handle 28 operated the type bars are moved into place and an impression corresponding with the numbers on the counter printed as previously described. At the time this is taking place the lever 80 is moving downward. The rack 60 167 having been disengaged from the pin 171 and having embraced the pin 187 carried by the lever 80 is also moving downward and revolving the gear 169 and the 65 shaft 170. When the lever 174 rocks after

the lever 80 has reached its lowest point the link 172 lifts the arm 173 and shaft 49, rocks the lever 178 and shifts the shaft 170 bringing the pins 185 carried by the shaft 170 into the planes of movement of the pins 70 188. As the lever 80 ascends the shaft 170 is rotated and the pins 188 engaging the pins 185 revolve the disks 184 till the counter wheels all stand with zero exposed through the sight opening. The counter 75 wheels are positively stopped when they reach zero (Fig. 6) by levers 189, carried by the tie links 190 which are thrown into the path of the pins 185 by the shaft 150. In case a counter wheel stands at nine when it 80 is reset it will be turned backward to zero and will therefore not throw the transfer mechanism. Counters standing at figures of lower value will move correspondingly less while one standing at zero will not be 85 moved.

It will be seen that the total may be printed without resetting the counter to zero but that totals may also be printed and the counter reset to zero at the same operation, 90 the resetting operation taking place as an incident to the movement of the grand total lever which connects the counter shaft to the main operating mechanism for operation thereby.

Some very small parts of the operation remain to be described, among which may be included the reset to normal position of the total key and the function lever, the provisions for locking the function lever 52 during the operation of the machine and the devices for releasing the keys. These will be described in the order named.

A link 191 (Fig. 6) is pivoted to the cam 60 and carries at its free end a pin 192 which 105 enters a curved slot 193 in the lever 160. At the very last part of the forward movement of the lever 28 the pin 192 engaging the lower end of the slot 193 rocks the lever 160 downwardly and positively restores the 110 levers 52 and 158, to their normal positions, the former into the position for addition. The lever 52 is returned to its central position in the same way by the lever 160 when a sub-total is printed.

The upwardly projecting arms 194 and 195 forming part of the lever 36 co-act with a pin 196 to prevent the lever 52 from becoming displaced while the handle 28 is moving. The horizontal groove 197 cut in 120 the arm 195 permits the restoration of the lever 52 when the lever 36 is elevated. The pin 171 co-acting with the edge of the rack 167 prevents the lever 158 from becoming displaced while the handle 28 is moving.

Depressed keys are released from the detent plates 21 at the end of each operation of the machine (see Fig. 7) by means of bell crank levers 201. The bell cranks 201 are mounted on two levers 199 which are 130

rigidly secured to a rock shaft 198. One of said levers 199 extends through the casing of the machine for convenience for setting by hand. Upon a shaft 200 mounted in the levers 199 are rigidly secured the bell crank levers 201, one of which has a horizontal extension and carries a pin 202 projecting into the path of the cam 60 so as to be struck by the part 203 of said cam at the latter part of its movement. A rod 204 carried by the levers 201 moves the detents 21 at the latter part of the forward movement of the handle 28 and releases depressed keys. By moving the lever 199 to the right 15 in Fig. 7, the pin 202 will be moved out of the path of the cam 60 and amounts set up on the key board may be repeatedly added. An extension 205 of the lever 52 will engage the pin 202 and release any keys that 20 may be depressed when the lever 52 is moved into position for printing a total.

A rack 206 forms part of the cam 60 and the co-acting pawl 207 is pivoted to the frame of the machine for the purpose of 25 compelling a full stroke of the lever 28 in both directions.

It may also be noted that the machine is adapted to be used as an adding machine solely by disabling the impression taking 30 mechanism. This may be accomplished by moving the adjustable lever 137 to the right (see Fig. 1) until the roller is in the extended notch 208 of the lever 126. In this 35 position of the parts, the movement of the lever 126 is not sufficient to give any movement to the adjustable lever 137, so that when the machine is operated, while the latches 210 for the hammers are tripped, still the springs 134 are not tensioned at all, 40 and consequently the hammers do not strike the type carriers but remain in retracted position.

While the form of mechanism here shown and described is admirably adapted to fulfil 45 the objects primarily stated, it is to be understood that it is not intended to confine the invention to the one form of embodiment herein disclosed for it is susceptible of embodiment in various forms all coming 50 within the scope of the claims which follow.

What is claimed is as follows:

1. In an accounting mechanism, the combination with a bank of keys, of a stop differentially adjustable by said keys, an operating mechanism having a constant excursion at each operation, actuating mechanism having its movement determined by said stop, gearing positively connecting the actuating and the operating mechanisms, and registering mechanism operated by said actuating mechanism.

2. In an accounting mechanism, the combination with a series of keys, of a stop adjustable by said keys, an operating mechanism having a constant excursion at each

operation, a rack bar having its movement determined by said stop, gearing positively connecting the actuating and the operating mechanisms, and registering mechanism operated by said rack bar.

3. In an accounting mechanism, the combination with a series of manipulative devices, and a stop differentially adjustable by said devices, of an operating mechanism having a constant excursion at each operation, complementary stepped actuating devices, gearing positively connecting the actuating devices and the operating mechanism, and co-acting with said stop, and registering mechanism operated by said stepped actuating devices.

4. In an accounting mechanism, the combination with a series of manipulative devices and a stop differentially adjustable by said keys, of a pair of actuating devices having complementary graduations, means for moving said devices until said graduations contact with said stop, and a registering mechanism driven by one of said pair of devices.

5. In an accounting mechanism, the combination with a series of keys and a stop differentially adjustable by said keys, of an operating gear bodily movable, actuating devices connected to said gear and having complementary graduations adapted to engage said stop, and registering mechanism operated by one of said devices.

6. In an accounting mechanism, the combination with a series of keys and a stop differentially adjustable by said keys, of slides having complementary graduations adapted to engage said stop, a gear connecting said slides, means for moving said gear bodily, and registering mechanism actuated by one of said slides.

7. In an accounting mechanism, the combination with a series of keys, and a stop bar differentially adjustable thereby, of an operating mechanism including a bodily movable gear, slides constantly meshing with said gear and provided with complementary graduations, said slides being adapted to be given different extents of movement depending on said stop, a registering mechanism, and means for bringing said mechanism and one of said slides into co-operating relation.

8. In an accounting mechanism, the combination with a series of keys and a stop bar differentially adjustable thereby, of a registering mechanism, a pair of graduated slides one of which drives said registering mechanism, means for connecting said slides, and means for moving said connecting means and thereby moving said slides until their graduations contact with said stop bar.

9. In an accounting mechanism, the combination with a series of keys, and a stop

bar differentially adjustable thereby, of an operating mechanism having a constant excursion at each operation and comprising a gear, slides having complementary graduations and engaging said gear, said graduations being adapted to engage said stop bar when the operating mechanism is given its excursion, and registering mechanism driven by the movement of one of said slides 10 in one direction.

10. In an accounting mechanism, the combination of a pair of plungers having oppositely stepped serrations; a pinion between and connecting said plungers; rack teeth on 15 said plungers for engaging the pinion; means for giving the pinion invariable excursions and a stop with means for moving said stop into alignment with any of the serrations on said plungers.

20. 11. In an accounting mechanism, the combination of a movable rack, a pinion in engagement with said rack, stops on said rack, a stop with means for moving it into alignment with any of the stops on said rack, 25 and means for giving the pinion excursions of invariable extent.

12. In an accounting mechanism, the combination with a bank of keys, of a plate moved by said keys, said plate being provided with a flange, and having a complementarily graduated pair of camming edges 30 for each key, and a registering mechanism controlled by said flange.

13. In an accounting mechanism, the combination with a series of keys, of a sliding plate having pairs of complementarily graduated camming edges engaged by said keys when depressed, and a locking edge connecting each pair of camming edges, together 35 with means for bringing the said plate to a zero position.

14. In an accounting mechanism, the combination with a series of keys, of a plate having pairs of differentially graduated 45 camming edges positioned to be engaged by said keys when depressed, the edges of each pair being complementary, and means for moving said plate to a zero position.

15. In an accounting mechanism, the combination with a series of keys, of a differential element having a pair of complementary camming edges for each key, the different pairs being differentially graded, and also having a stop flange, and registering mechanism controlled by said stop flange. 55

16. In an accounting mechanism, the combination with manipulative devices, of a determining member differentially movable in opposite directions by the manipulative devices, said determining member being provided with V shaped slots coacting with the manipulative devices. 60

17. In an accounting machine, the combination with a printing couple, of a hammer 65 for bringing the members of said couple to-

gether to effect an impression, a normally untensioned spring for operating said hammer, devices having an invariable movement at each operation for tensioning the spring independent of any movement of the hammer, and a latch for said hammer having connections to be tripped by the invariably moved devices after the spring is tensioned. 70

18. In an accounting mechanism, the combination with printing mechanism including 75 type carriers, of hammers for striking said carriers, an operating mechanism having a constant excursion, and a controlling device for said hammers having a connection to said operating mechanism adjustable to vary the force of the hammer blow.

19. In an accounting machine, the combination with a printing couple, of a hammer for bringing the members of said couple together to effect an impression, a member 85 having a constant excursion during each operation of the machine, and mechanism connecting the hammer with the movable member, the said mechanism being adjustable so as to vary the force of the hammer 90 blow.

20. In an accounting machine, the combination with a printing couple, of a hammer for bringing the members of said couple together to effect an impression, a member 95 having a constant excursion during each operation of the machine, a spring for operating the hammer, and mechanism connecting the spring with the movable member, the said mechanism being adjustable so as to vary the tension of the spring. 100

21. In an accounting machine, the combination with a printing couple, of a hammer for bringing the members of said couple together to effect an impression, a member 105 having a constant excursion during each operation of the machine, a rock shaft, a spring connected to the hammer and the rock shaft, and adjustable means connecting the movable member with the rock shaft so as to 110 vary the tension of the spring.

22. In an accounting mechanism, the combination with a printing mechanism including type carriers and a platen, of hammers for striking said type carriers to take impressions therefrom, an operating mechanism, an element having a variable connection to said operating mechanism, and a driving spring connected to said hammer and element. 115 120

23. In an accounting mechanism, the combination with type carriers, of hammers for taking impressions from same, said hammers having cut away portions, a rod positioned to engage the sides of said cut away portions, pivoted levers connected to said hammers near one of the cut away portions, and means for operating said levers. 125

24. In an accounting mechanism, the combination with type bars, of hammers for tak- 130

ing impressions from same, and cams for shifting said type bars against said hammers as the type bars reach a normal position.

- 5 25. In an accounting mechanism, the combination with registering mechanism, of a graduated cam controlled thereby, a lever constructed to be moved against said cam, a differential stop adjusted by said lever, 70
10 printing mechanism, and means for adjusting said printing mechanism to an extent dependent on said differential stop.

26. In an accounting mechanism, the combination with registering mechanism, of 75
15 printing devices and means for differentially adjusting same, a graduated cam controlled by said registering mechanism, and a stop differentially adjustable by said cam, said stop serving to determine the movement 80
20 of said adjusting means.

27. In an accounting mechanism, the combination with registering mechanism, of a graduated cam controlled thereby, a stop differentially adjustable by said cam, a 85
25 printing mechanism, an operating mechanism for said printing mechanism, and means for moving said operating mechanism to engage said adjustable stop.

28. In an accounting mechanism, the combination with registering mechanism, of a 90
30 stop device, means for differentially adjusting same under control of said registering mechanism, an adjusting mechanism, and means for moving same until stopped by 95
35 said stop device, and printing mechanism moved by said adjusting mechanism.

29. In an accounting mechanism, the combination with register wheels, of a shaft having transfer devices thereon, two racks 100
40 for separately rotating said shaft in opposite directions, and means for withdrawing one rack from operative position and moving the other rack into operative position simultaneously.

- 45 30. In an accounting mechanism, the combination with register wheels, of transfer devices therefor, a shaft carrying said devices, two racks for driving said shaft and devices in opposite directions, a common 105
50 controlling means for said racks, and connections which when operated withdraw one rack from driving position and move the other rack to driving position.

31. In an accounting mechanism, the combination with registering elements, and transfer mechanism therefor, of means for operating said mechanism in opposite directions as desired, actuating means for said operating means having an invariable excursion, and means for determining in which direction the transfer mechanism shall be moved.

32. In an accounting mechanism, the combination with registering mechanism, of actuating racks therefor, transfer devices be-

tween the elements of said mechanism, means for adjusting said racks so as to produce motion of said registering mechanism in either of two directions as desired, means for operating said transfer mechanism in either of two directions as desired, and a common means for controlling said adjusting means and said transfer operating means.

33. In an accounting mechanism, the combination with registering mechanism, and transfer devices therefor, of actuating racks for said mechanism, means for adjusting said racks so as to produce a reverse movement of said registering mechanism by operation of said racks, means for operating said transfer devices in opposite directions, and means connecting said adjusting means to said transfer operating means.

34. In an accounting mechanism, the combination with registering mechanism, and transfer devices therefor, of actuating devices for said mechanism, means for adjusting said actuating devices so as to produce motion of said registering mechanism in either of two opposite directions, operating devices for moving said transfer devices in either of two opposite directions as desired, and a common means for operating said adjusting means and controlling said operating devices.

35. In an accounting mechanism, the combination with registering mechanism, and transfer devices therefor, of operating devices for said mechanism adjustable to add or subtract as desired, transfer devices for said mechanism adapted to add or subtract by opposite movements of said devices, and a manipulative device for adjusting said operating devices and determining the direction of movement of said transfer devices.

36. In an accounting mechanism, the combination with a bank of keys and a stop differentially adjusted thereby, of complementarily graduated slides constructed to engage said stop, a type carrier moved with one of said slides of lower order and an additional stop for said slide controlled by the slide of next higher order.

37. In an accounting mechanism, the combination with pairs of slides, and means for positioning them, of type carriers one moved by one of each pair of slides, and a stop for the other of each pair of slides controlled by the movement from zero of the type carrier moving slide of next higher order.

38. In an accounting mechanism, the combination with a differentially adjustable stop, of a pair of complementarily graduated slides connected together, a second pair of slides of higher order also connected together, means for moving said slides until the desired graduations of said first slides engage said stop, type carriers moved by one of each pair of slides, and a stop for the

other of a pair of slides of lower order controlled by the type carrier moving slide of higher order.

39. In an accounting mechanism, the combination with registering elements, of transfer devices between said elements, a shaft on which said transfer devices are mounted, means carried by each registering element for sliding the corresponding transfer device on its shaft, and means for rotating said transfer device carrying shaft.

40. In an accounting mechanism, the combination with registering elements, of transfer devices between said elements, and a shaft carrying said transfer devices, cams carried by said elements for shifting the transfer devices on said shaft, means for rotating said shaft to engage the transfer devices with the registering elements, and operate said elements, said transfer devices having projections for reversely sliding them to normal position.

41. In an accounting mechanism, the combination with registering wheels, of transfer devices including pairs of operating projections between said wheels, a shaft carrying said transfer devices, cams carried by said wheels for sliding the transfer devices on their shaft, means for rotating the said shaft in either of two opposite directions as desired and thereby engaging one or the other of the pairs of projections with said registering wheels, and means for resetting said transfer devices.

42. In an accounting mechanism, the combination with registering wheels, having flanges with cut away portions, of transfer devices between said wheels comprising operating projections, and bent portions normally engaging said flanges, cams carried by said wheels for sliding said transfer devices on their shaft, the bent portions passing through the cut away portions of the flanges, means for rotating said shaft to engage the operating projections with the registering wheels, and means for resetting the transfer devices.

43. In an accounting mechanism, the combination with counter elements, of a printing mechanism, an operating mechanism for adjusting said printing mechanism under control of said counter element to print totals, means for resetting said counter elements to normal zero position, and a total lever for connecting said resetting means to said operating mechanism.

44. In an accounting device, the combination with a key and a key detent, of a main operating mechanism, a bell crank lever positioned to be engaged by an element of said main operating mechanism, and to release said key detent, and a lever for moving said bell crank out of the path of the said element.

45. In an accounting mechanism, the com-

bination with counter wheels, of means for printing totals therefrom, a sub-total lever controlling said printing, means for resetting said counter wheels, and a total lever and connections for adjusting said sub-total lever and for also causing operation of said resetting means.

46. In a machine of the class described, the combination with a counter element, of a rack for adjusting said element, a stepped slide, keys for arresting said slide in differential positions, a pinion connecting said rack and slide, and means for giving said pinion invariable excursions.

47. In a machine of the class described, the combination with a counter element, of a rack for adjusting said element, a pinion for driving said rack and means for giving said pinions invariable bodily excursions, a slide having a rack gearing with said pinion, a series of keys, and key controlled means for differentially positioning said slide.

48. In a machine of the class described, the combination with a counter element, of a rack for engaging and operating said element, a pinion driving said rack, means for giving said pinion invariable excursions bodily, a series of keys, means controlled by said keys for causing a determined part of said bodily movement of said pinion to compel a rotary movement thereof.

49. In a machine of the class described, the combination with a counter element, of a rack for engaging and operating said element, a pinion driving said rack, means for giving said pinion invariable bodily excursions, a slide connected to said pinion, a series of keys, and means controlled by said keys for obstructing said slide at different points.

50. In a machine of the class described, the combination with a counter element, of a rack for engaging and operating said element, a pinion for driving said rack, means for giving said pinion invariable bodily excursions, a bank of keys, a slide engaging said pinion and driven thereby, and devices projected by said keys into the path of said slide at different points.

51. In a machine of the class described, the combination with a counter element, of an element for driving the same, a pinion permanently connected to said driving element, means for giving said pinion invariable bodily excursions, a slide geared to and driven by said pinion, and means for obstructing the said slide at different points.

52. In a machine of the class described, the combination with a counter element, of an operating rack for the same, a driving device permanently geared to said operating rack with means for giving said driving device invariable bodily movements, connections whereby the bodily movement of said

- driving device may cause a rotary movement thereof, and a bank of keys, with key controlled connections for determining the extent of such rotary movement.
53. In a machine of the class described, the combination with a counter element having a driving gear, and an intermediate gear permanently connected to said driving gear and positioned parallel to but in a different plane from the counter driving gear, of a driving rack, means for actuating said rack, and means for shifting said rack into the planes of either of said gears.
54. In a machine of the class described, the combination with a counter element, having a driving gear and an intermediate gear permanently connected to but in a different plane from said driving gear, of a rack for driving said counter element normally in the plane of said driving gear, with connections for shifting said rack to bring it into the plane of the intermediate gear, and means for actuating said rack.
55. In a machine of the class described, the combination with a counter element, having a driving gear and an intermediate gear permanently connected parallel to but in a different plane from said driving gear, an actuating rack for said gears normally in the plane of the driving gear, a subtracting lever, and means actuated by said lever for shifting said actuating rack into the plane of the intermediate gear.
56. In a machine of the class described, the combination with a counter element, and a rack for driving same, of a lever for throwing said rack into and out of engagement with said counter element and having spaced projections, an operating handle, and a disk having spaced projections for positively engaging and operating the spaced projections of said lever in opposite directions with connections whereby said handle operates said disk in one direction only.
57. In a machine of the class described, the combination with a counter and its operating device and a printing mechanism, of means for adjusting said printing mechanism, keys controlling the operation of said means, and a connection from said adjusting means to said counter operating device comprising a bell crank lever pivoted to said adjusting means, having one arm pivoted to said counter operating device and the other arm having a camming edge.
58. In a machine of the class described, the combination with a printing mechanism, of adjusting means therefor, a counter and a counter operating device, a lever pivoted on said adjusting means, one arm being connected to said counter operating device and the other arm comprising a camming edge, and a rod with which said camming edge engages.
59. In a machine of the class described, the combination with a printing mechanism, of adjusting means therefor, a counter and a counter operating device, a lever fulcrumed on said adjusting means, and having one arm connected to said counter operating device, the other arm being provided with a camming and a straight edge, and a rod for engaging both said camming and straight edges.
60. In a machine of the class described, the combination with a printing mechanism, of adjusting means therefor, a counter and a counter operating device, a connection between said adjusting means and said counter operating device comprising a pivoted arm, and means for swinging said arm on its pivot during part of the movement of the adjusting means.
61. In a machine of the class described, the combination with a bank of keys and a key detent, of a hand operated lever, a bell crank lever pivoted thereon for actuating said detent, and a main operating mechanism, an element of which actuates said bell crank lever.
62. In a machine of the class described, the combination with a bank of keys and a key detent, of a pivoted hand lever, a lever pivoted thereon and positioned to release said key detent, a main operating mechanism including an element for actuating said releasing lever, and an adjustable device which when moved to one position also actuates said releasing lever.
63. In a cash register, the combination with a counter and transfer devices therefor, of means comprising a pair of racks for moving said transfer devices in opposite directions, an adjustable device, arms connected to each of the racks and having oppositely graded slots, and means for actuating said arms, connected to said function levers and comprising an element movable in said graded slots.
64. In a cash register, the combination with a counter and a transfer shaft therefor, of driving means comprising a pair of racks separately engageable with said transfer shaft, an adjustable device, devices having oppositely graded slots and connected to said racks, an arm actuated by said adjustable device and having a bearing in said slots, and means for reciprocating said racks.
65. In a cash register, the combination with a counter and a transfer shaft therefor, of separate means for rotating said transfer shaft in opposite directions, an adjustable device, and devices operated thereby for determining which of said separate means shall be effective.
66. In a printing mechanism, the combination with type carrying bars, and means for adjusting them to different extents, of impression devices, one for each bar, comprising type hammers and pivoted arms to

which said hammers are pivoted, a rod on which said hammers normally rest and around which they rotate, and means for rocking said pivoted arms around their 5 pivots;

67. In a printing mechanism, the combination with a type carrying element, and means for differentially adjusting it, of impression devices comprising a type hammer 10 and a pivoted arm on which said hammer is itself pivoted, means for rotating said pivoted arm, and a stationary device around which said hammer rotates when said pivoted arm is actuated.

15 68. In a printing mechanism, the combination with a type carrying element having a notch, of a pivoted hammer for taking impressions from said type element, and having a projection, a stationary piece which 20 said type element engages for camming said notch and projection together, and thereby locking said hammer, and means for actuating said hammer when the same is released.

69. In a printing mechanism, the combination with a type carrying element, and a hammer for taking impressions therefrom, of a pivoted arm for actuating said hammer, a driving element with means for giving the same invariable excursions, and a 30 link connecting said driving element and pivoted arm, having a projecting arm whereby the link may have its point of connection with the driving element manually shifted.

35 70. In a machine of the class described, the combination with a counter element, and a graduated device movable in correspondence therewith, of a printing mechanism, means for differentially adjusting said 40 printing mechanism, an element for obstructing said adjusting means at different points, an adjustable device, and devices actuated thereby for engaging said graduated device and constructed to move said obstructing element extents proportional to the graduation engaged.

71. In a machine of the class described, the combination with a counter element and a graduated device movable in correspondence therewith, of a printing mechanism, means for differentially adjusting said mechanism, a device for obstructing said mechanism in any differential position, an adjustable lever and a device moved thereby into contact with the graduations of said graduated device, constructed to engage and differentially adjust said obstructing device.

72. In a machine of the class described, the combination with a counter, a graduated 60 element movable therewith, and means for printing totals from said counter comprising a printing mechanism, devices engageable with the graduations of said element for determining the movement of said printing

mechanism and an adjustable lever causing movement of said devices, of a resetting lever and connections operated thereby for actuating said adjustable lever and for also causing the counter to be reset to normal zero position.

73. In a printing mechanism, the combination with a type carrier bearing a plurality of characters all of which are normally out of printing position, of a pair of complementary movable elements one of which is rigidly connected to the type carrier, manipulative devices for controlling the movement of said elements, operating means for imparting the combined movements of said elements to one of the elements 80 when none of the manipulative devices are operated, a second type carrier, and means controlled by the latter for arresting the element having the combined movement to enable the operating means to impart the 85 complementary movement to the companion element so as to bring one of the characters on the first mentioned type carrier to printing position.

74. In a printing mechanism, the combination with a plurality of type carriers each having a plurality of characters all of which are normally out of printing position, of a pair of complementary movable elements for each type carrier, the latter being connected 95 to one element of each pair, a series of keys for each type carrier to control the movement of same, operating means for imparting the combined movement of each pair of elements to one member thereof when no 100 keys are operated, and means actuated by the movement of any one of the type carriers for arresting the elements having the combined movement to the right of the adjusted carrier and thereby permit the complementary movement of the companion elements of the arrested ones so as to bring the type carriers to printing position.

75. In a printing mechanism, the combination with a plurality of type carriers each 110 having a plurality of digital characters, of a plurality of banks of manipulative devices for controlling same, movable elements corresponding in number to the type carriers, the said type carriers and movable 115 elements having complementary movements when the manipulative devices are operated and only the elements being moved when the manipulative devices are not operated, operating means for said type carriers and 120 movable elements, and means controlled by the adjustment of any one of the type carriers for bringing the zeros of the type carriers to the right thereof to printing position.

76. In a printing mechanism, the combination with a plurality of type carriers each having a plurality of digital characters, of

a plurality of banks of manipulative devices for controlling same, movable elements corresponding in number to the type carriers, the said type carriers and movable elements having complementary movements when the manipulative devices are operated and only the elements being moved when the manipulative devices are not operated, operating means for said carriers and movable elements, and means controlled by the movement of any one of the type carriers for arresting the movement of the movable elements corresponding to the type carriers of lower order so as to bring the zeros of the latter type carriers into printing position.

77. In a printing mechanism, the combination with a plurality of type characters each having a plurality of digital characters, of a plurality of banks of manipulative devices for controlling same, movable elements corresponding in number to the type carriers, the said type carriers and movable elements having complementary movements when the manipulative devices are operated and only the elements moving when the manipulative devices are not operated, operating means for said carriers and movable elements, and devices interposed by the movement of any one of the type carriers into the path of the movable elements corresponding to the type carriers of lower order so as to arrest the movement of the said elements and thereby bring the zeros of the corresponding type carriers into printing position.

78. In an accounting mechanism, the combination with a pair of complementary movable elements, of an operating mechanism therefor a type carrier rigidly connected to one of said elements, a registering element having a lost motion connection with the movable element to which the type carrier is connected and means for positively taking up the lost motion between the registering element and the movable element to which it is connected.

79. In an accounting mechanism, the combination with a pair of complementary movable slides, of an operating mechanism therefor, a series of manipulative devices controlling the movement of said slides, a type carrier rigidly connected to one of said slides, a registering element having a lost motion connection with the same slide to which the type carrier is connected, and means connected to the type carrier slide for positively taking up the lost motion between said slide and the registering element upon the operation of the operating mechanism.

80. In a machine of the class described, the combination with an operating mechanism having a constant excursion during

each operation of the machine, of a registering mechanism, and means having positive permanent connections with the operating mechanism for imparting a differential movement to the registering mechanism.

81. In a machine of the class described, the combination with an operating mechanism having a constant excursion during each operation of the machine, of a registering mechanism, and complementary movable elements positively connected at all times with the operating mechanism for imparting a differential movement to the registering mechanism.

82. In a machine of the class described, the combination with a registering mechanism, of an actuating mechanism therefor movable in different planes to add or subtract upon said registering mechanism and means for moving said actuating mechanism into the different planes.

83. In a machine of the class described, the combination with a registering mechanism comprising a plurality of differentially movable elements, of a pair of gears for each element of the registering mechanism, and an actuating mechanism for said registering mechanism constructed to be moved into engagement with one or the other of each pair of gears to add or subtract upon the registering mechanism.

84. In an accounting machine, the combination with a series of keys, of an element differentially positioned by said keys, an operating mechanism, and a spring put under tension by said mechanism and connected to return the differentially positioned element to normal position.

85. In an accounting machine, the combination with a series of keys, of an element differentially positioned by the operation of said keys, means for latching the keys in their operated positions, a normally untensioned spring connected to return the differentially positioned elements to normal position, and an operating mechanism having connections for operating the latching means and for tensioning the spring.

86. In an accounting machine, the combination with a hammer for striking a printing blow, of a normally untensioned spring for operating said hammer, an operating mechanism, and a member driven by said operating mechanism and having an invariable movement at each operation of said operating mechanism, and adjustable mechanism for connecting the spring to the invariable movable member so that the tension of the spring may be varied upon different operations of said operating mechanism for the purpose described.

87. In an accounting machine, the combination with a hammer for striking a printing blow, a normally untensioned spring for

operating said hammer, an operating mechanism, a member driven by said operating mechanism and having an invariable movement at each operation of said operating mechanism, adjustable mechanism for connecting the spring to the movable member so that the tension of the spring may be varied upon different operations of said operating mechanism, and latching means for 10 the hammer having connections to be tripped by the invariably movable member after the spring has been tensioned.

88. In an accounting machine, the combination with a printing couple, of a hammer 15 for bringing the members of said couple together to effect an impression, an operating mechanism, a member having an invariable movement imparted thereto at each operation of said operating mechanism, and adjustable mechanism for connecting the hammer and the invariably movable member for the purpose of varying the force of the hammer blow, the said mechanism also being so constructed as to disable the hammer.

25 89. In an accounting machine, the combination with a hammer for striking a printing blow, of an operating mechanism, a member having an invariable movement imparted thereto at each operation of said operating mechanism, a spring for operating said hammer, and adjustable mechanism for connecting the spring and the invariably movable member, for the purpose of varying the force of the printing blow, the said 35 adjustable mechanism also being so constructed as to disable the hammer.

90. In an accounting machine, the combination with a hammer for striking a printing blow, of an operating mechanism, a 40 member connected to be given an invariable movement by each operation of said operating mechanism, a spring for operating said hammer, and an adjustable link connecting the spring and the movable member, 45 the said link being adjustable so as to render the spring inoperative at will.

91. In an accounting machine, the combination with a hammer for striking a printing blow, of a spring for operating said 50 hammer, and a manipulative device for disabling the spring at will.

92. In an accounting machine, the combination with a hammer for striking a printing blow, a normally untensioned spring 55 for operating said hammer, a movable part of the machine having connections to tension the spring at each operation, thereof, and an adjustable link connecting the spring and the movable part, the said link being 60 adjustable so as to prevent the tensioning of the spring when desired.

93. In an accounting machine, the combination with counter elements, of a printing mechanism, an operating mechanism for ad-

justing said printing mechanism under control of said counter elements to print sub-totals and grand totals, manipulative devices for determining whether a subtotal or a grand total is to be printed, and resetting mechanism for the counter elements brought 70 into operation only when the grand total is to be printed.

94. In an accounting machine, the combination with counter elements, of a printing mechanism, an operating mechanism for adjusting said printing mechanism under control of said counter elements to print sub-totals and grand totals, manipulative devices for determining whether a subtotal or a grand total is to be printed, and resetting 80 mechanism for the counter elements constructed to be engaged with the operating mechanism by the grand total manipulative device only.

95. In an accounting machine, the combination with a series of depressible keys, of means for latching said keys in depressed position, and a determining member differentially adjusted by the keys, the construction of the latching means and the determining member being such that after a key has been latched in depressed position and the determining member thereby adjusted the latter member may be positively readjusted and the latching means operated to 90 release the latched key upon the operation of another key of the series.

96. In an accounting machine, the combination with a series of depressible keys, of a detent for latching said keys in depressed 100 position, and a determining slide differentially adjusted by the keys, the construction of the detent and the slide being such that after a key has been latched in depressed position and the slide thereby adjusted the 105 said slide may be positively readjusted and the detent operated to release the latched key upon the operation of another key of the series.

97. In an accounting machine, the combination with registering elements, of actuators therefor, combined transfer and locking devices normally in engagement with said elements, and means for withdrawing 110 said devices from engagement with the registering elements to permit operation of the latter by the actuators and then reengaging the transfer devices with the registering elements to effect a transfer.

98. In an accounting machine, the combination with registering elements, of actuators therefor, combined transfer and locking devices normally in engagement with said elements, and means for disengaging 115 said devices and elements to permit operation of the latter by the actuators and then reengaging said devices and elements to effect a transfer.

99. In an accounting machine, the combination with registering elements, of actuators therefor normally out of engagement therewith, combined transfer and locking devices normally in engagement with said elements, and means for engaging the actuators and elements and disengaging the combined transfer and locking devices and said elements to permit operation of the latter by the actuators and then reengaging said devices and elements to effect a transfer.

100. In an accounting machine, the combination with registering elements, of combined transfer and locking devices therefor normally in engagement therewith, actuators for said elements, means for engaging and disengaging the devices and elements, and means controlled by the registering elements for positioning the transfer devices while the latter are out of engagement with said elements so as to effect a transfer when the devices and elements are reengaged.

101. In an accounting machine, the combination with registering elements, of combined transfer and locking devices therefor normally in engagement therewith, means for engaging and disengaging the devices and elements, means for positioning the transfer devices while the latter are out of engagement with the registering elements so as to effect a transfer when the devices and elements are reengaged, and means controlled by the registering elements for rendering the transfer devices ineffective after a transfer has taken place.

102. In an accounting machine, the combination with registering elements, of combined transfer and locking devices therefor normally in engagement therewith, a shaft carrying said devices, means for engaging and disengaging the devices and elements, mechanism controlled by the registering elements for positioning the transfer devices while the latter are out of engagement with said elements so as to effect a transfer when the devices and elements are reengaged, and means for rotating the shaft carrying the transfer devices while the latter are in engagement with the registering elements thereby effecting a transfer.

103. In an accounting machine, the combination with registering elements, of normally ineffective transfer devices therefor, actuators for said elements, means controlled by the registering elements for preventing said devices from being rendered effective at other than a predetermined point in the movement of said elements, a shaft carrying said devices, and means for rotating the shaft and thereby effecting the transfer.

104. In an accounting machine, the combination with registering elements, of normally ineffective transfer devices for said elements, mechanism carried by the transfer

devices and engaging the registering elements for preventing the accidental rendering of said transfer devices effective, and means controlled by said elements for positively rendering the transfer devices effective.

105. In an accounting machine, the combination with a printing couple, of a hammer for bringing the members of said couple together to effect an impression, a normally untensioned spring for operating said hammer, a member having an invariable movement at each operation of the machine for tensioning the spring, and manipulative means whereby said invariable movement can be made to give the spring different degrees of tension so as to vary the force of the hammer blow.

106. In a printing mechanism, the combination with a differentially moved type carrier, of impression devices comprising a hammer to strike the type carrier and a pivoted arm on which said hammer is itself pivoted, means for rotating said pivoted arm; a stationary device around which said hammer rotates when said pivoted arm is actuated, and means whereby the hammer will engage the stationary device after striking the type carrier, thereby positively preventing the hammer from rebounding against the type carrier.

107. In an accounting machine, the combination with a printing couple, of a hammer for bringing the members of said couple together to effect an impression, a normally untensioned spring for operating said hammer, devices having an invariable movement at each operation for tensioning the spring, a latch for said hammer having connections to be tripped by the invariably moved devices after the spring is tensioned, and means for relatching the hammer after the spring has returned to normal condition.

108. In an accounting machine, the combination with a plurality of type carriers, of a platen, means for differentially adjusting said type carriers relative the platen, hammers for operating the carriers to make impressions, means normally restraining the hammers from operation, means for tripping said restraining means, and means whereby a type carrier in non-adjusted position will prevent the operation of the corresponding hammer after the aforesaid restraining means is tripped.

109. In an accounting machine, the combination with a type carrier, of means for differentially adjusting same, a hammer for striking a printing blow, a normally untensioned spring for operating said hammer, an invariably moved element, devices operable to connect the spring to the invariably moved element and adjustable to give said spring different degrees of tension, latching means

for the hammer having connections to be tripped by the invariably moved element after the spring has been tensioned, and means whereby the type carrier when in non-adjusted position will prevent operation of the hammer after said connections are tripped.

In testimony whereof I affix my signature in the presence of two witnesses.

FRANCIS K. FASSETT.

Corrections in Letters Patent No. 1,132,711.

It is hereby certified that in Letters Patent No. 1,132,711, granted March 23, 1915, upon the application of Francis K. Fassett, of Dayton, Ohio, for an improvement in "Registering Mechanism," errors appear in the printed specification requiring correction as follows: Page 10, line 77, before the comma insert the words *co-acting with said stop*; same page, line 79, strike out the words "and co-acting with said stop"; page 14, line 107, strike out the words "function levers" and insert the words *adjustable device*; and that the said Letters Patent should be read with these corrections therein that the same may conform to the record of the case in the Patent Office.

Signed and sealed this 11th day of May, A. D., 1915.

[SEAL.]

R. F. WHITEHEAD,

Acting Commissioner of Patents.

DISCLAIMER.

1,132,711.—*Francis K. Fassett*, Dayton, Ohio. REGISTERING MECHANISM. Patent dated March 23, 1915. Disclaimer filed July 19, 1926, by the assignee by mesne assignments, *The National Cash Register Company*.

Hereby enters this disclaimer to that part of the claim in said specification which is in the following words, to wit:

"61. In a machine of the class described, the combination with a bank of keys and a key detent, of a hand operated lever, a bell crank lever pivoted thereon for actuating said detent, and a main operating mechanism, an element of which actuates said bell crank lever."

[*Official Gazette August 17, 1926.*]

DISCLAIMER.

1,132,711.—*Francis K. Fassett*, Dayton, Ohio. REGISTERING MECHANISM. Patent dated March 23, 1915. Disclaimer filed August 11, 1926, by the assignee by mesne assignments, *The National Cash Register Company*.

Hereby disclaims any structure which falls within claim 95 of said patent, except that in which the positive readjustment of the determining member is effected by the depression of another key without the use of springs.

[*Official Gazette August 31, 1926.*]

for the hammer having connections to be tripped by the invariably moved element after the spring has been tensioned, and means whereby the type carrier when in non-adjusted position will prevent operation of the hammer after said connections are tripped.

In testimony whereof I affix my signature in the presence of two witnesses.

FRANCIS K. FASSETT.

Witnesses:

Roy C. GLASS,
CARL J. BENST.

Corrections in Letters Patent No. 1,132,711.

It is hereby certified that in Letters Patent No. 1,132,711, granted March 23, 1915, upon the application of Francis K. Fassett, of Dayton, Ohio, for an improvement in "Registering Mechanism," errors appear in the printed specification requiring correction as follows: Page 10, line 77, before the comma insert the words *co-acting with said stop*; same page, line 79, strike out the words "and co-acting with said stop"; page 14, line 107, strike out the words "function levers" and insert the words *adjustable device*; and that the said Letters Patent should be read with these corrections therein that the same may conform to the record of the case in the Patent Office.

Signed and sealed this 11th day of May, A. D., 1915.

[SEAL.]

R. F. WHITEHEAD,

Acting Commissioner of Patents.

DISCLAIMER.

1,132,711.—*Francis K. Fassett*, Dayton, Ohio. REGISTERING MECHANISM. Patent dated March 23, 1915. Disclaimer filed July 19, 1926, by the assignee by mesne assignments, *The National Cash Register Company*.

Hereby enters this disclaimer to that part of the claim in said specification which is in the following words, to wit:

"61. In a machine of the class described, the combination with a bank of keys and a key detent, of a hand operated lever, a bell crank lever pivoted thereon for actuating said detent, and a main operating mechanism, an element of which actuates said bell crank lever."

[*Official Gazette August 17, 1926.*]

DISCLAIMER.

1,132,711.—*Francis K. Fassett*, Dayton, Ohio. REGISTERING MECHANISM. Patent dated March 23, 1915. Disclaimer filed August 11, 1926, by the assignee by mesne assignments, *The National Cash Register Company*.

Hereby disclaims any structure which falls within claim 95 of said patent, except that in which the positive readjustment of the determining member is effected by the depression of another key without the use of springs.

[*Official Gazette August 31, 1926.*]

DISCLAIMER.

1,132,711.—*Francis K. Fassett*, Dayton, Ohio. REGISTERING MECHANISM. Patent dated March 23, 1915. Disclaimer filed October 18, 1926, by the assignee by mesne assignments, *The National Cash Register Company*.

Disclaims any structure falling within claims 25, 26, 27, and 28, except such as specified below, to wit:

“Claim 25. With respect to claim 25, all structures are disclaimed except those in which the ‘differential stop’ is a single stop variably positioned, and the means for adjusting the printing mechanism comprises complemental differentially adjustable members cooperating with the said stop.

“Claim 26. With respect to claim 26, all structures are disclaimed except those in which the ‘stop differentially adjustable’ is a single stop, and the means for differentially adjusting the printing devices comprises complemental differentially adjustable members cooperating with said stop.

“Claim 27. With respect to claim 27, all structures are disclaimed except those in which the ‘stop differentially adjustable’ is a single stop, and the means for moving the printer operating mechanism comprises complemental differentially adjustable members cooperating with said stop.

“Claim 28. With respect to claim 28, all structures are disclaimed except those in which the ‘stop device’ is a single stop, and the adjusting mechanism for moving the printing mechanism comprises complemental differentially adjustable members cooperating with said stop.”
